UNITED STATES PATENT OFFICE.

CHARLES NICHOLSON, OF BROOKLYN, NEW YORK.

STREET-CAR FENDER.

SPECIFICATION forming part of Letters Patent No. 678,023, dated July 9, 1901.

Application filed April 3, 1900. Renewed May 22, 1901. Serial No. 61,467. (No model.)

To all whom it may concern:

Be it known that I, CHARLES NICHOLSON, a citizen of the United States of America, and a resident of New York city, borough of Brooklyn, State of New York, have invented new and useful Improvements in Street-Car Fenders, of which the following is a specification.

This invention relates to certain new and useful improvements in fenders and bumpers for use on cars; and its object is to provide a fender which will surely and certainly protect any person accidentally struck by it from being injured either by the fender or the car and also provide a means for lowering the fender, that it may with certainty pass under the person if lying in its path.

In the accompanying drawings similar letters indicate corresponding parts.

Figure I shows my improved fender and bumper-cushion in place. Fig. II shows bumper-cushion alone with fender removed. Fig. III shows fender and bumper both raised up out of service. Fig. IV shows a front view of fender and bumper and lever-ratchet. Fig. V shows the tripping device for raising and lowering the fender. Fig. VI shows the inside cam for holding the brace-rod C of the fender in position in the socket in the hanger a.

Referring more particularly to the drawings, A A designate sides of the fender-frame, A' A' the end cross-bars of the fender-frame, and B the net attached to the frame. This frame and net are sometimes called the "scoop."

C is a cross-bar at the near end of the frame A and so arranged as to enter at each side of the car a socket G, made in the hanger a.

D is the guide-rod of the spring-actuated buffer situated in front of the fender or scoop. This buffer is provided with springs b b, and the loops c c hold the rod D in place and guide it and allow it to be pressed down upon the springs b b.

Attached to the outside of the hangers a a is the cam d, one on each hanger, and the rod e passes through the hangers a a, and to it are attached the cams d.

E is a regulating-lever ratchet passing down through the platform of the car and pivoted to the arm s, which is secured to the rod e. The

regulating-lever ratchet E is provided with a handle i at the top, by means of which it may be raised or lowered, and on its face is provided with teeth f f, which lock upon the base of the tripping device and hold the lever-ratchet firmly in position. From the dashboard there extends the spring g, which presses against the lever-ratchet and prevents the teeth from slipping away from their holding. Back of the lever-ratchet and situated on the floor of the platform is the foot-tripper h, which is so arranged that by pressing it down it pushes back the lever-ratchet E, the teeth become disengaged, and in turn the rod e revolves and disengages the cams d d, and thus the front end of the fender or scoop is allowed to fall upon or very close to the ground, thereby making it certain that it will pass under any person or object lying in front of it. On the inside of the hanger a is a cam k, which slips over the cross-bar C and engages it and holds it in place and prevents it from springing out of the socket G by the jolting or action of the car. On the front of the car is what I term the adjustable "bumper-cushion" F, provided with a frame of iron and springs attached thereto. It has the handle l to raise it up or pull it forward and allow it to drop down over the end of the car when in use. (See Fig. 1.) At each end are the pivotal joints m m—one at top and one at bottom of the frame of the bumper—which act as hinges and also hold the bumper in place. The lower pivotal joint has a slot at o, which allows the lower end of the bumper to be pushed back and upon a seat or rest n when the bumper is not in use. Between the two pivotal joints is a locking-pivot p, which falls down and rests upon the lower pivotal joint, and thus prevents the bumper from springing up and down while the car is in motion.

The operation of my invention will be seen to be of great usefulness and advantage. The spring-actuated bumper D in front of the fender prevents to a large degree any violent or hard blow to the person accidentally struck. It would prevent breaking any limbs. The springs being at the point of contact before and not after the weight of the fender strikes the object makes it a very great improvement.

over those now in general use, and the location of the springs in front prevent the objectionable up-and-down oscillation of the fender, and the adjustable bumper-cushion F is 5 so arranged and located that the body strikes against springs held in position by a strong framework, and thus prevents the person striking the solid framework of the car. The regulating-lever ratchet allows the front end 10 of the fender to descend and pass under the body in front, and thus prevents any such possible accident as the car-wheels passing over the body. By lifting the lever-ratchet E by the handle i the pivot-joint s turns the 15 brace-rod e and causes the cams d d to press upon the end of the fender-frame beneath, thus lowering the rear end and raising the front end of the fender. By pressing with the foot upon the foot-tripper h it presses 20 against the lever-ratchet E and pushes it back, releasing the teeth f from their holding, and thus causes the lever-ratchet E to descend and turns the arm s, which releases the cams 25 d d from any pressing on the rear ends of the fender-frame, thus allowing the rear end of the fender-frame to rise up and the front end to fall down. The spring g keeps the ratchet-lever in place and prevents the teeth f from slipping away by the action of the car.

30 My fender or scoop is of great value, because it can be so easily disengaged from the car by raising the cams k k on the inside of the hangers a a, and thus slipping the cross-bar C out of the sockets G, and the fender being light, although strong, is easily carried to the other end of the car and is adapted to any make of car.

35 By my invention there is provided for street-cars a simple, effective, and efficient method 40 of catching and retaining the body of any person accidentally struck while the car is in motion.

It will be seen by reference to Fig. 1 that by my method of having the bumper-cushion 45 disconnected from the scoop a body falling on my fender will be protected from the bumper by the cushion and from that will fall into the scoop. The scoop, which is nearly at right angles to the cushion, being practically in a 50 horizontal position, will prevent any rebound, and a body once in the scoop the netting forms a bag shape, making it impossible to roll off to the ground.

By my method of having the scoop independent I not only give a greater surface for 55 retaining any body that falls into it, but it also projects from twelve to eighteen inches less in front of the car-bumper than the fenders now in use. This feature is specially desirable when a car is turning curves or on crowded thoroughfares; also, in connection 60 with its light weight when placed on four-wheel cars, does not add as much to the oscillation of the cars as a heavy projecting fender would.

In the ordinary fender now in use, constructed with the bumper or cushion and scoop parts practically in one and hanging on an incline to the ground, a body rebounds or easily rolls off.

Another advantage of my invention is that when the car is housed the fender A and bumper F are raised up, allowing the cars to be practically run up close together, thus economizing space.

There is a great saving of material and cost in my invention, because the two side bars A and two end cross-bars A' of the fender or scoop are made of the same size and are interchangeable, so that any railroad need only 70 keep about five different parts of my invention in stock, and thus be at all times prepared to repair any damage done to the fender or scoop. These parts are the side bars A A and the cross-bars A' A', the net B, the 75 springs b b, and loop C. The frame, being of steel, can easily be straightened, if bent, thus making the cost of maintenance very small.

Those parts of my invention attached to the car will last generally as long as the car itself. 80

Having described my invention, what I claim is—

1. A car-fender having an independent adjustable bumper-cushion, scoop-hangers with slot for holding the scoop, connecting braces, 95 cams and shafts and automatic locking-catches, the scoop arranged to fit in hanger-slots and regulated by the action of the cams, operated by the regulating-lever.

2. In combination with the car, the bumper-cushion F provided with the joints or arms m, m and the seat n, for the bumper-cushion, substantially as described and set forth.

3. In combination with the car, the scoop-hangers a, a, having the socket G, the connecting cam-rod e, provided at each end with the cams d, d substantially as described and set forth.

4. In combination with the car, the foot-tripper h, the regulating-lever ratchet E, provided with teeth f, the spring g, the cam-shaft e and arm s, pivoted to the lever-ratchet E, the cams d, d and hangers a, a having the socket G, substantially as described and set forth.

5. In combination with the car, the fender-frame A, A and A', A' the hangers a, a, the cam-shaft e, and cams d, d, the inside locking catches or cams K, substantially as described and set forth.

6. In combination with the car the fender or scoop having frame A, A and A', A', the hangers a, a, provided with socket G, the brace-rod C to fit in the socket G, the regulating-lever ratchet E provided with teeth f, 125 the spring g, the cam-shaft e, and arm s, pivoted to the lever-ratchet E and secured to the cam-shaft e and cams d, d, the foot-tripper h, substantially as described and set forth.

7. In combination with the car, the adjust- 130

able bumper-cushion F, provided with the pivotal joints m, m at each end, the lower one being made with a slot o, to allow the base of the bumper-cushion to fall back and rest upon the seat n, substantially as and for the purposes set forth.

5 In testimony that I claim the foregoing as

my invention I have signed my name, in presence of two witnesses, this 23d day of January, 1900.

CHARLES NICHOLSON.
